UNITED STATES PATENT OFFICE.

AMOS PERRY, OF SAN FRANCISCO, CALIFORNIA.

SIGN BOX.

Application filed September 13, 1921. Serial No. 500,417.

To all whom it may concern:

Be it known that I, AMOS PERRY, a citizen of the United States, residing at the city and county of San Francisco and State 5 of California, have invented new and useful Improvements in a Sign Box, of which the following is a specification.

This invention relates to a sign box, such as employed on street-cars, etc., and especially to a web winding and tensioning 10 device therefor.

In sign boxes such as employed on street-cars, it is common practice to employ a long fabric web or belt on which is printed or 15 otherwise displayed street names, stations and the like. The web is generally carried by a pair of rollers and is wound from one to the other when it is desired to change the street name or station displayed. Considerable trouble is encountered, such as buckling, 20 folding, wrinkling, etc., where a web of this character is repeatedly transferred from one roller to another due to the fact that it is difficult to maintain a constant or sufficient 25 tautness in the web at all times.

The object of the present invention is to generally improve and simplify devices of this character, and especially to provide a winding and tensioning mechanism which 30 will exert a constant pull on the web at all times, thus largely overcoming the difficulties above mentioned.

Further objects will hereinafter appear.

The invention consists of the parts and 35 the construction, combination and arrangement of parts as hereinafter more fully described and claimed, having reference to the accompanying drawings in which—

Fig. 1 is a side elevation of the sign box.

40 Fig. 2 is a central, vertical, longitudinal section.

Fig. 3 is an enlarged transverse sectional view of the sign box.

Referring to the drawings in detail, A indicates a box-like structure, in one side of which is formed a window or display opening 2. Journalled longitudinally of the box and mounted interior thereof is a pair of upper and lower rollers generally indicated 45 at 3 and 4. The roller 4 is secured on a shaft which is turnably mounted in journals 5 and 6, while the roller 3 is supported in journals 7 and 8. The roller 4 is rigidly secured on the shaft supporting the same and 50 therefore turns in unison with the shaft. The roller 3, while free to rotate in its jour- 55

nals, is however supported in a different manner. By referring to Fig. 2, it will be seen that one end of the roller is solid as indicated at 3, and that this solid portion is 60 rigidly secured to a pin or shaft extension 9, which enters the journal member 7. The roller 3 is surrounded by a tube 10, and forming a closure for the opposite end of the tube is a plug or bushing 11, through 65 which extends a shaft 12. It will thus be seen that the upper roller consists of a solid section and a hollow section or tube. This shaft is supported at one end in the journal member 8, and it extends through the bushing 11 and enters the forward end of the roller 3; it being freely turnable in the bushing and in the roller. A driving connection is however formed between the shaft 12 and the roller 3 and tube 10, which is resilient; 70 such resilient drive being formed by surrounding shaft 12 with a spring 13; one end of the spring being secured to the shaft, as at 14, while the opposite end is secured to the roller and tube 10, as indicated at 15. 75 The rollers are provided for the reception of a fabric web or belt 16, upon which is printed or displayed a series of street names, stations or the like, as indicated at 17, see Fig. 1. One end of the belt is secured to the 80 tube 10, while the opposite end of the belt is secured to the roller 4. The belt is wound about the respective rollers and the portion extending between the rollers is that which displays the street or station named. 85

Whenever it is desired to change the street name displayed, it is only necessary to impart a turning movement to the rollers to bring the next name into register with the display opening. Such turning movement, 90 when it is desired to change the street station name displayed, is imparted by a mechanism generally indicated at B. The mechanism consists of a bracket 18 secured in one end of the housing. Extending cross- 95 wise of the bracket and journalled therein, is a shaft 19, on one end of which is secured a bevel gear 20 and a sprocket gear 21. Also journalled in the bracket and extending at right angles thereto is a shaft 22. Secured on the inner end of the shaft and meshing with the bevel gear 20, is a bevel gear 23, and secured on the outer end of shaft 22 is a hand crank 24, by means of which rotary movement is transmitted to the 100 shafts 22 and 19. Secured on the inner end of the shaft 12 is a sprocket gear 25. Simi- 105

2
larly secured on the roller shaft 4 is a sprocket gear 26, and forming a driving connection between the sprocket gear 21 and the sprockets 25 and 26 is an endless driving chain 27.

In actual practice it is obvious that the belt 16 will have considerable length as it is generally necessary to provide a considerable number of street or station names, particularly when the tracks extend over a large territory. This web or belt is, as previously stated, carried by the rollers 3 and 4, and is wound from one roller to the other as street changes are required. It is therefore obvious that one roller or the other will increase in diameter as the web is being wound or unwound, and that considerable slack will be permitted if some compensating means is not provided. This is due to the fact that the sprockets 25 and 26 have a common pitch diameter, and are driven in unison. Such slack however is avoided in the present instance and a constant tension or pull is exerted regardless of whether the belt is being wound in one direction or another; this constant tension being maintained by the spring 13. For instance if the belt is being wound about the roller 4, and this increases in diameter with relation to that portion which is wound about the roller 3, it can be seen that as both rollers are driven in unison, the tension on the belt will increase to such an extent that it might part. This is avoided in the present instance as the roller 3 and tube 10 can turn independently of the shaft 12, due to the resilient connection formed by the spring 13. In other words the speed of rotation of roller 3 and tube 10 would increase under that condition and spring 13 would be partially wound. If the operation of winding is reversed, and the roller 3 presents a smaller diameter than the roller 4, it is obvious that the speed of rotation of roller 3 will have to be greater than the speed of rotation of the roller 4 as it is obvious that a considerable amount of slack would accumulate between the rollers. Such increased speed is automatically taken care of by the spring 13 as this was placed partially under tension when the web was being unwound. As the diameter of the roller 3 increases, the speed of rotation will gradually decrease and when the diameters are equal, the speed will be equal as sprockets 25 and 26 are equal in diameter. Again as the diameter of the roller 3 increases, the speed will decrease, while the speed of rotation of roller 4 remains constant. In fact the roller 4 will be driven at a constant speed at all times, but

the speed of rotation of the roller 3 automatically increases or decreases as conditions demand, thus maintaining the belt or web in a taut condition at all times, and avoiding such objections as buckling, folding or wrinkling of the web, etc.

The mechanism employed is exceedingly simple, no attention being required on the part of the operator as the mechanism is entirely automatic in action. In fact his only duty is that of rotating the crank 24 when a change in display is required. The entire structure of the roller 3 is, practically speaking, identical to an ordinary window shade roller. It may therefore be mounted in a similar manner so that it may be removed with relation to the sprocket 25 and the bearing 7. With this object in view the outer end of the shaft 12 entering the sprocket 25, may be flattened as indicated at 12^a. This permits it to be removed when required and at the same time permits a driving connection to be established between the sprocket and the shaft.

Having thus described my invention, what I claim and desire to secure by Letters Patent is—

A device of the class described, including an oblong casing provided at its opposite ends with upper and lower bearings, a pair 90 of upper and lower spaced horizontal rollers mounted in the said bearings, the upper rollers consisting of a solid section and a tube fitted on the solid section and extending therefrom to form a housing, a plug arranged within the outer end of the tube, a shaft extending through the plug into the tube and having its inner end mounted in the solid section of the upper roller, said shaft being extended outwardly beyond the 100 said plug and mounted in one of the said bearings, a coiled spring housed within the tube and disposed on the said shaft and connected at one end with the same and at the other end with the tube and the hollow section, a short horizontal shaft located within the casing at one end thereof, sprocket wheels also arranged within the casing and mounted on the said shafts and on the said lower roller, a sprocket chain arranged on the said 110 sprocket wheels, a belt wound upon and carried by the said rollers, an operating shaft extending through the casing to a point adjacent the horizontal shaft at right angles to the same, bevel gears connecting the operating shaft with the horizontal shaft, and a bracket mounted within the casing and supporting the short horizontal shaft and the operating shaft.

AMOS PERRY.
